SLIP STITCH SEWING MACHINE

Herman Rosenman and Leo Roseman,
Newark, N. J.

Application April 19, 1935, Serial No. 17,160

30 Claims. (Cl. 112—2)

This invention relates to a sewing machine especially for skipping or slipping of stitches in a line of stitches according to a method described and claimed in the application of Herman Rosenman filed February 19, 1935, Serial No. 7223.

While our machine is useful for many purposes, it is particularly desirable for stitching together two or more plies or thicknesses of material with continuous lines of stitches where in at predetermined intervals stitches are skipped or slipped to form gaps between two adjacent plies to receive fastener elements such as hooks or eyes for example to form fastener tape or to receive clasps of clasp steels or the like at the edges of corsets.

Our invention contemplates a machine wherein a needle forms a loop in the thread which is picked up by a loop taker and interlocked with another thread, for example, from a bobbin mechanism, for completing a stitch during normal operation of the machine, although the invention is susceptible to use with other types of sewing machines, including multiple needle machines.

It has been proposed to skip stitches in a line of stitches formed by a sewing machine, either by interrupting the reciprocation of the needle bar so that the needle is prevented from penetrating the work, or by throwing the needle bar out of cooperation with the loop taker of the bobbin mechanism, or by throwing the loop taker out of cooperating relation with the needle, so that the loop taker cannot pick up the loop which is formed by the needle during normal operation in making a stitch. All of these machines involve complex mechanisms and operations and require modification of the usual stitch forming mechanism for accomplishing the skipping of stitches, and furthermore in these machines no provision is made to take up or compensate for the surplus thread which results from the skipped stitches, so that the thread tangles.

In other cases, stitches are skipped under manual control of the operator, the work being preliminarily marked to indicate the points at which the skipping is desired and the machine operator being required to stop the machine at intervals when the marks reach the needle, then pull the work forward the distance of the skip while the needle is out of the work, and then start the machine to resume the line of stitches. Due to the manual control the stitching is often inaccurately done so that the skips are not prop-

erly located, and the operation is tedious and slow.

Prime objects of our invention are to provide a sewing machine embodying novel and improved features of construction whereby one or more stitches can be slipped or skipped automatically by manipulation or control of the thread independently of the normal stitch forming mechanism of the sewing machine instead of modifying or manipulating the loop taker of the bobbin mechanism or the needle bar; and to provide such a machine whereby the skipped or slipped stitches shall be located accurately and automatically by the machine and the operation of forming a line of stitches including skipped or slipped stitches shall be rapid and require a minimum of manual effort and attention. Our invention is particularly directed to means for pulling of the thread so as to prevent the formation of a loop in the thread and thereby prevent cooperation of the loop taker with the needle thread to prevent the formation of a stitch or stitches.

In normal operation, the loop of course requires a predetermined quantity of thread, and the loop is formed normally during withdrawal of the needle from the work but before the needle is disengaged from the work. In accordance with our invention novel and improved means is provided to exert tension on the needle thread during withdrawal of the needle from the work and at the same time withdraw from the work in timed relation to the movement of the needle a predetermined or measured quantity of thread which is necessarily present to permit formation of a loop to cooperate with the loop taker, so as to ensure that enough thread shall be withdrawn to prevent formation of the loop and at the same time the thread shall not be broken by excess tension.

Further objects are to provide in a machine of the character described novel, improved and simple means for controlling or withdrawing the thread automatically in a regular cycle in timed relation to the movement of the needle and independently of or without affecting the normal operation of the stitch forming mechanism or the work feed mechanism of the machine; and thus to provide such a machine which shall be capable of forming a line of stitches in the usual way, in combination with novel and improved mechanism for gripping the thread at a certain time above the eye of the needle while the needle is in approximately its uppermost position and preferably while the thread is taut between the

point of gripping and the point of interlocking of the thread in the work on the last previously formed stitch, then manipulating the thread in timed relation to the movement of the needle to prevent formation of a stitch, and thereafter releasing the grip on the thread whereby it shall be possible to form a line of stitching having skipped stitches spaced along the line accurately at desired intervals.

10 Further objects are to provide such a machine which shall include novel and improved means for timing the spacing of the skipped or slipped stitches so that said skipped stitches may be located at predetermined intervals; and thus to 15 provide means preferably actuated approximately synchronously with the drive shaft and needle bar of the machine for pulling or manipulating the thread, in combination with means operable in timed relation with but at slower speed than 20 said drive shaft and needle bar to control the gripping of the thread by the pulling or manipulating means.

Another object is to provide a machine of the character described which shall include novel and 25 improved means for moving or controlling the surplus thread that is present due to skipping of a stitch, so that said surplus thread shall be prevented from becoming entangled with the needle and thereby obviate breaking of the thread during 30 formation of subsequent stitches.

In many cases, it is desirable that a skipped stitch be located a certain distance from the edge of a piece of work at the beginning of the stitching operation, and therefore another object of my 35 invention is to provide novel and improved indicator means for pre-setting the machine so that the first skipped stitch in a piece of work shall be located at the desired distance from the edge of the work at the beginning of the stitching operation, or to indicate the number of stitches that 40 have been made after a slip stitch.

It is often necessary that the slipped stitches be exactly spaced in the work, especially in making a fastener strip where the gaps resulting from 45 the slipped stitches are intended to receive fastener elements to cooperate with complementary fastener elements on another fastener strip; and therefore our invention contemplates mechanism for slipping or skipping stitches including a reciprocating feed dog, in combination with auxiliary positive work advancing means ahead of the feed dog, for example continuously rotating feed rollers to grip the work between them, for preventing underfeeding or overfeeding of the 50 work by the feed dog.

In applying strips to the edge of a garment and skipping or slipping stitches to leave gaps for fastener elements, as hereinabove described, it is 55 desirable in many instances that the slip stitches be located in certain relations to the garment, for example that the last slipped stitch be spaced a certain distance from the end of the garment, and the operator can see that with continued feeding of the work with normal or usual feed 60 of the work, the last slipped stitch will not be properly located. Therefore, another object is to provide such auxiliary work advancing means in combination with the usual feed dog work feed mechanism whereby the feed of the strips and 65 garment may be modified at the will of the operator for various purposes, for example, to cause the last slipped stitch to be located at least approximately at the desired point.

A further object is to provide novel and improved means in a machine of the character de- 70

scribed for throwing the thread gripping or controlling mechanism out of or into operation at will, so that it shall be possible to form a continuous line of stitches without skipping stitches whenever desired.

Other objects are to provide means which can be applied to many known types of sewing machines for controlling or manipulating the thread without modification of the usual stitch forming mechanisms or work feed mechanisms, and to 10 obtain other advantages and results as will be brought out by the following description.

Referring to the accompanying drawings, in which corresponding and like parts are designated by the same reference characters,

Figure 36 is a perspective view of two superposed strips of fabric for a fastener tape having 45 two lines of stitches formed with a two needle machine and having corresponding slipped stitches to form a gap for a fastener element, and

50 Figure 37 is a similar view showing a line of stitches formed with an oscillatory or so-called zig-zag machine and having a slipped stitch.

For the purpose of illustrating the principles of our invention we have shown it schematically in connection with a known type of sewing machine which includes the usual frame 1 having the usual stitch forming mechanism including a 55 needle bar A reciprocable therein by known mechanism (not shown). The needle bar carries the usual needle 3, and the machine also includes a take-up lever 4 which is utilized for supplying 60 and taking up the thread in cooperation with the loop taker. The needle has the usual eye 6 and the longitudinal groove 7 at one side in which the thread is seated as the needle penetrates and is removed from the work which is designated W.

65 Cooperating with the needle bar is the bobbin mechanism B of known type which includes a loop taker hook 8 to pick up the loop formed in the needle thread during the normal operation of the machine in the formation of a stitch.

70 The machine also includes suitable known work feed mechanism which includes the reciprocating feed dog R for advancing the work beneath the needle in steps each equal to the length of one stitch, and a presser foot P of known structure 75 is included to hold the work against the feed

dog. For the sake of simplicity these parts are only schematically and fragmentarily illustrated.

As usual, the thread T is threaded from a supply spool or the like through the tension device 5, the eye of the take-up lever 4 and the eye of the needle 6, and during normal operation of the machine, the needle reciprocates and on its descent penetrates the work to carry the thread through the work as shown in Figure 13 of the drawings. As the needle rises, normally the 10 thread at one side of the needle frictionally engages the work while the thread at the other side of the needle is in the groove 7, so that as the needle rises a loop L in the thread is formed below the work, as shown in Figure 14, and this loop is 15 picked up by the loop taker 8, carried around and interlocked with the bobbin thread to form a stitch S indicated in Figure 30. After the needle leaves the work, the work feed mechanism R moves the work forwardly a distance equal to the 20 length of one stitch, preparatory to the next work penetrating movement of the needle for the next stitch. When the needle is in its uppermost position, the thread between the take up lever and the point in the work where the threads are inter- 25 locked to form the last previously formed stitch, is substantially taut, and there is sufficient thread present to form a loop for the next stitch.

As above indicated, when it is desired to slip a stitch, we propose to manipulate or control the 30 thread T so as to prevent the formation of the loop L; and when it is desired to slip a stitch control of the thread is preferably started while the needle is in approximately its uppermost position, while when it is desired to resume 35 formation of normal stitches after one or more stitches have been slipped, control of the thread is released while the needle is in approximately its uppermost position.

Now specifically describing the thread gripping 40 and pulling mechanism, said mechanism includes a gripper G which comprises two gripping jaws 10 and 11 one of which is fixedly connected to a horizontal tubular shaft 12 which is mounted on a bearing bracket 13 secured on the goose-neck of 45 the machine. The other jaw 11 is mounted on the end of a rod 14 which is slidable longitudinally of the tubular shaft 12 with one end projecting from the tubular shaft and in abutting relation to an adjustable screw 15 mounted in one end of 50 a lever 16 which is pivotally mounted at 17 in the bracket 13 and connected to one end of a follower lever 18 which carries a roller 19 that follows a cam 20. The two jaws 10 and 11 are in juxtaposed relation and receive the thread T between 55 them, and the jaws are normally influenced together by tension spring 21 connected to a pin 22 which is fixed in the jaw 11 and slidable through the jaw 10 transversely of the latter.

The pin 22 causes the jaws to swing together 60 about the axis of the shaft 12. As shown, the jaws are mounted for oscillation in a vertical plane which is approximately the plane of the portion of the thread between the take up lever 4 and the needle.

The jaws are oscillated and in timed relation with the drive shaft D of the machine and the needle bar by a cam 23 which is mounted on the drive shaft (see Figure 7). The cam 23 cooperates with the follower roller 32 which is connected to a lever 31 pivotally connected at one end at 33 on the machine and connected at its other end by a link 34 to a crank arm 35 on the tubular shaft 12. The roller 32 is caused to follow the cam 23 by a spring 36.

The cam 23 is so shaped and timed that the thread gripper G is located at its uppermost position as shown in Figure 3 when the needle reaches its uppermost position and the gripper is 5 swung downwardly approximately synchronously with the movement of the thread T of the needle so that the gripper is in its lowermost position shown in Figures 4 and 9 when the needle reaches its lowermost work penetrating position shown in 10 Figure 13. As the needle rises the cam 23 actuates the gripper upwardly into the position shown in Figures 3 and 7. The gripper jaws 10 and 11 as so controlled by means about to be described that during the withdrawal of the needle from 15 the work the gripper pulls out an amount of thread that is present for forming a loop so as to prevent formation of a loop as shown in Figure 15. During the movement of the needle to the point which locates the thread above the loop 20 taker 8, the movement of the gripper is in advance of the movement of the needle to ensure pulling out of the thread that is present for normal formation of the loop, and during the remainder of the upward movement of the needle 25 the gripper preferably moves at a speed to prevent the thread beneath the gripper becoming entangled with the point of the needle and this obviates breaking of the thread during formation of subsequent stitches.

30 The gripper jaws 10 and 11 are actuated toward and from each other to grip and release the thread by the cam 20 which actuates the follower lever 18, lever 16 and rod 14. This cam 20 is mounted on a vertical countershaft 24 journaled 35 in suitable bearings 25 connected to the goose-neck of the machine and is driven by worm and worm gear drive 26 from the drive shaft D of the machine at a reduced speed. The speed ratio between the shaft D and 24 may be as desired, for 40 example so that the shaft 24 will make one revolution for a given number of stitches. One stitch is made during each revolution of the shaft D as usual, and as shown the speed ratio is twelve to one; in other words the cam 20 will make one 45 revolution while the drive shaft D is making twelve revolutions which during normal operation of the machine will result in the formation of twelve continuous stitches for each revolution of the cam 20. In the present instance it is desired 50 that one stitch shall be slipped in each series of twelve stitches, in other words, that eleven continuous stitches shall be formed and then one stitch shall be slipped. For this purpose the cam 20 has a concentric dwell 27 with which the follower roller 19 contacts during the formation of 55 eleven stitches, and a cam recess 28 which the follower roller engages during the interval required for formation of one stitch by the stitch forming mechanism.

60 The spring 21 normally holds the follower roller 14 in contact with the cam 20 and when the gripper is in its approximate upper position the gripping jaws are separated so as to release the thread as shown in Figure 7, the follower roller 65 and cam being in the relative positions shown in Figure 6. As the follower roller 20 enters the cam recess 28, the jaws are drawn together to grip the thread approximately simultaneously with the beginning of a downward movement of 70 the gripper jaws, and the gripping relation to the thread is maintained throughout the work penetrating movement of the needle approximately synchronously with the movement of the thread. As the needle begins to rise, the cam 23 75 and connected parts swing the gripper jaws up-

wardly slightly in advance of the normal movement of the thread so as to pull the thread out of the work to prevent the formation of a loop as shown in Figure 15. The gripper need move in advance of the thread only during the movement of the needle to the point which locates the thread above the loop taker so as to ensure pulling out of the thread that is present for normal formation of the loop, and during the remainder of upward movement of the lever the gripper 15 preferably moves at a speed to take up the thread beneath the gripper so as to prevent the thread from becoming entangled with the needle. Approximately as the gripper jaws reach their upper position the follower roller is forced out of 20 the cam recess as shown by Figures 10 and 11 so as to release the thread, and thereafter the machine will continue to make stitches because while the gripper jaws may be continuously oscillated they cannot grip the thread and therefore cannot 25 pull out the thread to prevent formation of stitches. With this construction it will be observed that in operation of the machine, eleven continuous stitches will be formed followed by skipping of one stitch, after which eleven more 30 stitches will be formed and so on.

Obviously by modifying the cams 20 and 29—133 two or more stitches might be skipped in succession, and by varying the timed relation between the stitch forming mechanism and the 35 thread gripping mechanism, the intervals at which the skipped stitches will be formed may be varied.

It is desirable to prevent oscillation of the gripper during the normal formation of stitches 40 both to prevent unnecessary wear on the thread gripping mechanism and to avoid unnecessary noise. For this purpose, the cam 20 may have a concentric cam surface 29 engaged by a roller 30 mounted on the lever 31 to hold the follower 45 roller 32 out of contact with the cam 23 as shown in Figure 7 except during the operation of skipping a stitch. To permit operation of the gripper for skipping the stitch, the cam surface may be interrupted by a recess 133 in proper relation to the cam recess 28 to permit the roller 30 to drop and thereby enable the follower roller 32 to follow the cam 23 as shown in Figure 9.

It will readily appear to those skilled in the art that the cam 23 and follower roller 32 might 50 be eliminated, and the cam notch 133 modified to actuate the lever 31 and shaft 12 through roller 30 instead of using the notch 133 simply as a clearance for the roller 30 to permit the roller 32 to follow the cam 23.

It will be understood that during the pulling of the thread the work feed R will have moved the work forwardly in the normal way a distance equal to the length of one stitch and the needle will have penetrated the work so as to leave a hole 60 O in the work as shown in Figure 30. Preferably the jaws will be released from the thread slightly before they reach their uppermost position of Figures 3 and 7 and will be held released from the thread by the cam dwell 27 a sufficient time 65 to permit the take up lever 4 to adjust the thread for the next stitch.

It will be observed that the thread is maintained substantially taut between the needle and the gripper throughout the reciprocation of the 70 needle from the beginning of its descent as shown in Figures 3 and 7 to its lowermost work penetrating position shown in Figures 4 and 13, and then through its upward movement back to its uppermost position; and due to the constant grip 75

on the thread during the movement of the gripper there is ensured the exact and measured amount of thread between the point of gripping and the interlock of the thread in the last previously formed stitch, by reason of which formation of the loop may be positively prevented and breaking of the thread is obviated. Preferably the grip by the jaws on the thread is frictionally yielding so that the thread may be pulled through the 10 jaws to compensate for slight irregularities or variations in the normal feed of the thread to the needle, or variations in timing of the loop taker.

It will be observed that our invention makes 15 possible a simple mechanism operable in regular cycles and which is substantially independent of operation of the stitch forming and work feed mechanism of the machine.

Where it is desired to throw the thread gripping and pull mechanism out of operation, for example to form a continuous line of stitches without skipping stitches, we may utilize a control device including a lever 40 pivotally mounted intermediate its ends at 41 on the machine and 23 which may be manually operated. One end of the lever has a pin and slot connection 42 with a control slide 43 mounted in the top of the machine to cooperate with an extension 44 on the lever 31. The slide 43 moves transversely of the extension 44 and has a lug 45 at its extremity and an inclined or wedging surface 46 adjacent said lug. When the gripper has been moved to its upper position as shown in Figures 3 and 7 the slide may be pushed beneath the extension 44 35 as shown in Figure 18, and upon continuation of this movement of the slide the wedge or inclined portion 46 will engage the extension to swing the gripper further upwardly to clear the follower roller 22 from the cam 23 as shown in Figures 19 and 28 and thereby completely disconnect the gripper from the driving mechanism. Therefore, it will be observed that with the parts in the 40 positions shown in Figures 19 and 20, the gripper cannot operate, and in order to permit operation of the gripper the slide 43 must be disengaged from the extension 44 as shown in Figure 18. Due to the lug 45 operation of the gripper cannot be started until it reaches its upper position because as shown in Figure 20 any attempt to disengage the slide 43 from the extension 44 50 while the gripper is below its uppermost position is prevented by engagement of the lug 45 with the extension.

It will also be observed that when the gripper 55 is in its intermediate or lower positions as shown in Figures 4 and 9 the slide cannot be slid under the extension 44 as shown in Figures 9 and 17 and therefore the operation of the gripper cannot be stopped until it has reached its uppermost 60 position as shown in Figures 7 and 18.

From the foregoing, it will appear that the thread gripping and pulling mechanism may be thrown into and out of operation at will by operation of the lever 40, and when out of operation it will always be located at its uppermost position as shown in Figures 3 and 7. While the thread gripping mechanism is out of operation the stitch forming and work feed mechanism will make a continuous line of stitches, while when the control slide 43 is disengaged from the extension 44, a stitch will be skipped at predetermined intervals, in the present instance every twelfth stitch.

Preferably the follower roller 19 will be thrown 75 out of operative relation to the cam 20 when

oscillation of the thread gripper is stopped by the control slide 43 and for this purpose, the lever 40 may have a lug 450 to engage the follower lever 18 so as to swing the latter to slide the gripper jaw 11 away from the jaw 10 simultaneously with the movement of the control slide 43 beneath the extension 44. Obviously, the lever 40 will be so mounted as to overcome the resistance of the spring 21. As shown, the lever 40 and slide 43 are mounted on a plate 50 secured 10 to the top of the goose-neck of the machine, and the follower lever 18 projects through a slot 51 in said plate.

While the form of the gripper jaws 10 and 11 may be considerably varied, a satisfactory structure is shown in the drawings, particularly Figures 4 and 5 wherein one of the gripper jaws has a spring wire loop 52 through which the thread is passed and which holds the thread in approximately proper relation to the gripping 20 surface of the jaws, and the other jaw has a guide plate 53 formed with a slot 54 to receive the thread and hold it in exactly the proper relation to the gripping surfaces. The movable jaw may move relatively to the guide plate 53. 25

In some cases it may be desirable to form a groove 196 in one of the gripping jaws of a depth less than the diameter of the thread to ensure that the thread shall always be gripped between the same portions of the gripping surfaces. 30

A modification of the invention is shown in Figures 21 to 28 inclusive wherein different means than that herein above described is utilized for separating the gripper jaws. This means is 35 shown as comprising a block 60 mounted on the machine above the gripper jaws and having a wedge 61 disposed to enter between the jaws when the latter are swung to their uppermost position. The jaws are oscillated in a vertical plane by 40 the same mechanism shown in Figures 1 and 7 and are normally influenced toward each other into thread gripping relation in the same manner as shown in Figures 1 and 7, namely by the spring 21. In operation, when the gripper 45 is in approximately its uppermost position, the gripping jaws are brought into engagement with the wedge 61 and are separated by the wedge so as to release the thread as shown in Figure 26, the upward movement of the gripper under the influence of the cam 23 forcing the jaws 10 and 50 11 over the wedge so that the jaws are spread apart; and when the cam 23 permits the gripper to move downwardly under the influence of the spring 36, the jaws are slipped off the wedge 55 and moved together by the spring 21 to grip the thread as shown in Figure 27.

For controlling the oscillation of the jaws so as to skip a stitch at proper intervals, we utilize a cam 63 having a surface similar to the cam 60 surface 29 and mounted on the countershaft 24 and formed with a cam notch 64 to cooperate with a roller 65 corresponding to the roller 30 of Figure 7. One revolution of the cam 63 corresponds to twelve stitches and while the roller 65 65 is in engagement with the flat cam dwell 66, the gripper jaws are held in their uppermost position, separated by the wedge 61. When the cam has been rotated to the point where the roller 65 may drop into the notch 64, the gripper jaws 70 are swung downwardly under the influence of the spring 36 under control of the cam 23, and are then raised by the cam 23 to move the roller 65 out of the notch so as to be again engaged by the dwell 66. The speed and character of 75

- movement of the gripper jaws is under control of the cam 23, the notch 64 serving merely to release the follower roller 32 into engagement with the cam 23 at the time that a stitch is to be skipped. The operation of the machine is otherwise the same as that of the machine shown in Figures 1 to 11 inclusive, the cam 63 and wedge 61 in effect taking the place of the cam 20, the follower roller 19 and the levers 16 and 18.
- 10 To illustrate the character of the skipped or slipped stitch formed by the machine, we have shown in Figure 30 complete stitches S and a slipped or skipped stitch K. It will be noted that between the two stitches S the needle thread T 15 and bobbin thread T-T have not been interlocked as they are at U when the stitches are formed.

Furthermore to illustrate one possible use of the machine we have shown in Figures 31 to 34 20 inclusive work of one type that can be performed with the machine. In Figure 31 are shown two plies of material 70 and 71 stitched together adjacent their edges by a line of stitches 72 including a skipped stitch 73. In Figure 32 the 25 two plies are shown as folded backwardly upon each other after stitching, and Figure 33 illustrates the two folded plies with a gap 74 therebetween left by the skipped stitch 73. In Figure 34 the two plies of material are shown as having 30 between them a fastener strip 75 which has a fastener such as a wire eye 76 projecting through the gap 74. The structure shown constitutes one type of garment fastener and may be embodied directly in the edge of a garment or 35 may be composed of strips of material which may be secured to the edges of a garment.

In making such fastener tape, it is highly desirable that the gaps 74 be accurately spaced, and our machine makes this possible automatically. 40 The usual feed dog work feed mechanism is not sufficiently reliable to produce the necessary accuracy and to ensure that the work shall be fed uniformly and accurately, we utilize an auxiliary feed mechanism to cooperate with the usual feed dog illustrated in Figure 3. This auxiliary feed mechanism includes two serrated feed rollers 80 and 81 between which the material to be operated upon is gripped, one roller being mounted in the frame of the machine on shaft 83 and the other 45 mounted on a shaft 84 in a frame 840 pivoted at 841 so that roller 81 may be influenced toward roller 80 by a spring 842. The rollers are geared together to rotate at the same peripheral speeds by intermeshing pinions 82, one on each of the 50 roller shafts 83 and 84, and one of the shafts, in the present instance the shaft 83, is driven by a helical gear connection 85 with a jack shaft 86 which has a helical gear connection 87 with the counter-shaft 24. The rollers 80 and 81 more 55 firmly grip the work than do the presser foot and feed dog, and feed the work accurately in timed relation to the stitch forming mechanism. The feed dog is normally adjusted to feed a length of work slightly greater than the length supplied 60 by the feed rollers for each stitch to ensure that the full amount of work shall be brought to the needle, and the pressure of the feed dog on the work is such that it may slip beneath the work after it has fed the exact amount controlled by 65 the feed rollers. With this construction, the work 70 is positively gripped between the feed rollers 80 and 81 and the rollers are constantly rotated at a uniform speed in timed relation to the drive shaft D and the needle, so that the work may be 75 fed with extreme accuracy and the skip stitches

73 may be accurately spaced in the work and overfeed of the work is prevented. Underfeed also is prevented by the adjustment of the dog R to feed more than desired, and the preventing of excess feed by the rollers 80, 81 which hold back the work to the feed desired, the dog slipping slightly over the work to compensate therefor.

In many cases it is desirable to locate the first 10 skipped stitch a predetermined distance from the edge of the work at the beginning of the stitching operation and to indicate the number of 15 stitches that have been made after a skipped stitch when the machine is stopped; and to accomplish this result we have shown an indicator 20 disc 97 mounted on the countershaft 24 and having a series of graduations 98 corresponding in 25 number to the number of stitches to be made in the work per inch. As shown, there are twelve graduations corresponding to twelve stitches per 30 inch, and for convenience the zero graduation corresponds to a skipped stitch. The disc 97 operates with a pointer 99 mounted in convenient relation on the machine, and the parts are so related that when the follower roller 19 engages the cam recess 28 for skipping a stitch the zero graduation on the indicator stitch is in juxtaposition to the pointer 99. Therefore should it be desired to form six stitches inwardly from the edge of the work at the beginning of the 35 stitching operation before skipping a stitch the drive shaft D will be rotated until the graduation "6" on the disc 97 is juxtaposed to the pointer 99. Then upon operation of the machine six stitches will be formed followed by a skipped 40 stitch, and then continued operation of the machine will result in the formation of eleven continuous stitches followed by a skipped stitch, and so on. To assist the operator in beginning 45 operation upon the next piece of work without unnecessary stopping of the machine, we mount on the disc a visible indicator 100 which may be a set screw adjustable circumferentially of the disc, and this visible indicator will be set in 50 juxtaposition to the graduation on the disc 45 which is in juxtaposition to the pointer at the beginning of the stitching operation, in the foregoing example, the graduation "6". Then when the end of one piece of work has passed the needle the operator will watch until the visible 55 indicator 100 reaches the pointer 99 whereupon the machine will be stopped. Then the next piece of work may be inserted into the machine and operation resumed with the assurance that the first skipped stitch on the second piece of 60 work will be spaced the same distance from the edge as was the skipped stitch in the first piece of work. This feature is particularly important where a long piece of facing strip to receive fasteners is to be stitched to a plurality of garments in succession.

In such cases the facing strip is fed through the feed rollers 80, 81, but the garments are laid on top of the strip and do not pass through the feed rollers; and in some cases it is desirable to 65 slightly modify the feed of the tape and the garments especially where it is necessary that the last slipped stitch shall be spaced approximately a certain distance from the end of the garment at the completion of the stitching operation. 70 In normal operation this distance may vary for different reasons, particularly because of slight differences in the length of the garments due to 75 inaccurate manufacture.

The sewing machine has the usual mechanism 75

generally designated A—A in Figure 2 such as shown in United States Patent No. 718,988 dated January 27, 1903 for adjusting the length of stitch through varying the extent of travel of the feed dog, such mechanism being regulated by a knob N at the end of the drive shaft D, or mechanism as shown in Patent No. 1,574,185 may be used. Should it be found that with normal feed, the last slipped stitch will be too far from the garment end, the feed mechanism will be adjusted to increase the length of stroke of the feed dog. Except for our feed rollers this would ordinarily increase the length of stitches by increasing the length of the steps of feeding of the work, but in the present case the tape is held back by the feed rollers and the material is substantially non-stretchable so that the length of the stitches is not increased. However, the feed dog does exert greater tension on the tape than during normal feeding and takes up any slight slack there may be between the feed dog and the rollers, and the garment follows the tape between the feed dog and the presser foot a distance greater than the length of a normal stitch. The pressure of the presser foot on the work is less than the pressure exerted on the work by the feed rollers 80 and 81, and the tape is held by the feed rollers while the garment is not so held, so that the tape is under tension and the garment is not under tension. Therefore, at the end of the feeding movement when the feed dog retracts from and releases the tape and before the needle penetrates the garment and tape, the tape slightly retracts sliding beneath the garment, and the garment remains at the point to which it was fed. This results in there being slightly more of the garment than of the tape traversed by the stitch; in other words, the garment is slightly taken up or puckered and accordingly the length of stitches remaining the same, the last slip stitch will be located closer to the end of the garment. Should the operator discover that the last slip stitch with normal feed will be too close to the end of the garment, the garment may be held back manually against the influence of the feed dog. Ordinarily this would result in changing the length of the stitches and distance between the slip stitches, but with our machine, due to normal tendency of the feed dog to overfeed, the backward tension or pull on the garment is compensated for by the overfeed, and as the tape is not retarded the length of stitches or spacing between the slip stitches is not changed. However, the last slip stitch will be located farther from the garment end.

Obviously, these adjustments of the feed may be used in connection with other machines for skipping or slipping stitches in different ways, and are not limited to our particular form of thread manipulating mechanism.

While we have so far described the invention in connection with a single needle machine, it may be used with a multiple needle machine. For example, another needle may be placed in the place provided in the needle bar A alongside the needle 3, and threaded as is the needle 3. Then the gripper may be modified as shown in Figure 35 by forming the thread guide plate 90 with a hole 92 to receive both threads, or two holes close together each to receive one thread so that both threads may be located between the gripping surfaces 94 and 95. If desired the plate 90 may have a screw and slot connection 91 with the gripper jaw 11 so as to slide longitudi-

nally of the jaw in either direction to move the threads from between the gripping surfaces 94, 95 when it is not desired to slip stitches. With this construction two parallel lines of stitches 101 may be formed as indicated in Figure 36 and both threads may be caused to slip stitches 102 at the same time and in juxtaposition.

This is important in securing fasteners with long shanks in the gaps between the plies of material beneath the slip stitches with the inner 10 row of stitches adjacent the base of the fastener, to prevent the material being slid backwardly along the shanks so as to expose the latter.

A similar effect can be obtained with a so-called zig-zag stitching machine having an oscillatory needle which may be periodically oscillated to form transverse stitches 103 at opposite sides of a slipped stitch 104 as shown in Figure 37. The transverse stitches 103 serve the same function as the two lines of stitches of 101 in preventing the fabric strips from sliding along the shanks of fasteners that are disposed beneath the slipped stitches.

It will be observed that in all forms of the invention the characteristic features are the skipping stitches by pulling of the thread instead of by modifying or manipulating the stitch forming mechanism or the bobbin mechanism, and the means for controlling the skipping of the stitches is substantially independent of the stitch forming mechanism and work feeding mechanism. Moreover, the mechanism is simple and reliable in operation, and due to the particular combination of the means for controlling the gripping of the thread by the thread gripper and the means for oscillating the thread gripper, it is possible to throw the mechanism out of operation during the formation of a normal line of stitches so as to reduce wear on the parts and thereby ensure long life thereof. This is particularly important in connection with the cam 23 and the follower roller 32 since undue wear of these parts would materially affect the accuracy of the operation of the gripper jaws, it being understood that a very delicate relationship must obtain between the movement of the gripping jaws and the thread and needle to ensure pulling out of the thread loop and at the same time obviate breaking of the thread.

Furthermore, due to the independent relation of our thread manipulating mechanism to the stitch forming and work feed mechanism of the sewing machine, the machine may be operated at substantially its usual high speed; our invention does not hinder, impede or slow the speed of stitching as would be the case were the operation of the needle bar or bobbin mechanism modified to slip stitches.

Having thus described our invention, what we claim is:

1. In a machine of the character described the combination with work feed mechanism and stitch forming mechanism including a reciprocating needle and a loop taker operable in timed relation for forcing a thread through a piece of work forming a loop in the thread at one side of the work and interlocking another thread through said loop to normally form a line of stitches, of means to grip the needle thread, and means operable in timed relation to the movement of the needle thread by the needle to actuate said gripping means automatically into gripping relation to the thread at intervals, and means for actuating said gripping means in timed relation to the movement of the needle thread by the

needle to exert tension on the thread as the needle rises from work penetrating position to prevent formation of loops.

2. The machine set forth in claim 1 wherein 5 the means for operating the gripping means to grip the thread and said means for actuating the gripping means in timed relation to movement of the needle, actuate the thread gripping means as the needle rises from the work to maintain the 10 thread substantially taut between said gripping means and the point of interlocking of the threads in the last previously formed stitch.

3. In a machine of the character described the combination with work feed mechanism and 15 stitch forming mechanism including a reciprocating needle and a loop taker operable in timed relation for forcing a thread through a piece of work, forming a loop in said thread at one side of the work and interlocking another thread 20 through said loop, of a gripper for gripping the needle thread above the needle, means operable at slower speed but in timed relation with said needle for automatically actuating said gripper at intervals to grip said thread while the needle 25 is above the work and maintain said grip during movement of the needle into and out of the work, and means operable approximately synchronously with said needle during a portion of each of the descending and ascending movements of the 30 needle but at slightly greater speed during the first portion of the movement of the needle from the limit of its work penetrating position to actuate said gripper to exert tension on the needle thread and prevent formation of a loop.

35 4. The machine set forth in claim 3 wherein the means for automatically actuating the gripper at intervals actuates said gripper to grip said thread when the needle is at approximately its uppermost position and also actuates said 40 gripper to release said thread while the needle is at approximately its uppermost position.

5. In a machine of the character described the combination with work feed mechanism and 45 stitch forming mechanism including a reciprocating needle and a loop taker operable in timed relation for forcing a thread through a piece of work, forming a loop in said thread at one side of the work and interlocking another thread 50 through said loop, and a drive shaft and operative connections between it and said stitch forming mechanism, of a gripper to grip the needle thread above the needle, a cam shaft geared for reduced speed to said drive shaft, a cam on said 55 cam shaft and operatively connected to said gripper for actuating said gripper at intervals to grip said thread while the needle is at approximately its uppermost position, and to release said thread while the needle is in said position, and a cam 60 on said drive shaft operatively connected to said gripper for moving the gripper approximately synchronously with said needle during a portion of the descending and ascending movements of the needle but at a greater speed than the needle during the first portion of its movement from the 65 limit of its work penetrating position to exert tension on the needle thread and prevent formation of loops.

6. In a machine of the character described the combination with work feed mechanism and 70 stitch forming mechanism including a reciprocating needle and a loop taker operable in timed relation for forcing a thread through a piece of work, forming a loop in said thread at one side of the work and interlocking another thread 75 through said loop, of a gripper including two

opposed jaws normally yieldingly influenced toward each other to grip the needle thread above the needle, means for moving said gripper approximately synchronously with said needle during a portion of each of the descending and 5 ascending movements of the needle but at slightly greater speed during the first portion of the movement of the needle from the limit of its work penetrating position, means for starting and stopping said movement of said gripper while 10 the needle is at approximately its uppermost position, and stationary means to be engaged by and separate said jaws to release the thread when the needle is at approximately its uppermost position and to release said jaws and to 15 grip said thread as the needle begins its descent from said uppermost position, whereby said gripper will pull said thread as the needle rises from its work penetrating position to prevent 20 formation of a loop.

7. The machine set forth in claim 1 wherein 25 said gripping means includes two relatively movable opposed jaws and spring means for normally yieldingly drawing them together to grip the thread, and said means for actuating the gripping 30 means to grip the thread relatively moves said jaws to separate them and permits the spring means to move them toward each other.

8. The machine set forth in claim 1 wherein 35 said gripping means includes two relatively movable opposed jaws and spring means for normally yieldingly drawing them together to grip the thread, and a horizontal shaft connected at one end to both said jaws to oscillate the jaws in a vertical plane with the needle thread between 40 them, said means for actuating the gripping means to grip the thread relatively moves said jaws to separate them and permits the spring means to move them toward each other, and the means for actuating the gripping means in timed 45 relation to movement of the needle thread by the needle oscillates said shaft.

9. The machine set forth in claim 1 wherein 50 said gripping means includes two relatively movable opposed jaws, said means for actuating the gripping means to grip the thread includes a cam operatively connected to one of the jaws to control movement of the latter toward and from the other jaw, and a horizontal shaft connected at one end to both said jaws to oscillate the 55 jaws in a vertical plane with the needle thread between them, and said means for actuating the gripping means to exert tension on the thread includes a cam rotatable in timed relation to the movement of the needle, and an operative connection between said cam and said shaft to oscillate said gripping means.

10. The machine set forth in claim 1 with the addition of a common means independent of the stitch forming mechanism for controlling starting and stopping of the means for actuating the gripping means to grip the thread and the means for actuating the gripping means to exert tension on the thread.

11. The machine set forth in claim 5 with the addition of means for connecting and disconnecting said gripper from said two cams independently of the operation of said stitch forming mechanism.

12. The machine set forth in claim 6 with the addition of means for controlling starting and stopping of the means for moving the gripper with the needle independently of the stitch forming mechanism.

13. The machine set forth in claim 1 with the

addition of means for controlling starting and stopping of the means for actuating the gripping means to grip the thread and the means for actuating the gripping means to exert tension on the thread independently of the operation of said stitch forming mechanism and only while the needle is at approximately its uppermost position.

14. The machine set forth in claim 3 with the addition of means for controlling starting and stopping of the means for actuating the gripper to grip the thread and the means for actuating said gripper to exert tension on the thread independently of the operation of said stitch forming mechanism and only while the needle is at approximately its uppermost position.

15. The machine set forth in claim 5 with the addition of a control slide to separably engage the operative connection between said cam on the drive shaft and said gripper when the needle is at approximately its uppermost position to disconnect and hold disconnected said operative connection from said cam to stop movement of said gripper independently of said stitch forming mechanism.

16. The machine set forth in claim 5 with the addition of a control slide to separably engage the operative connection between said cam on the drive shaft and said gripper when the needle is at approximately its uppermost position to disconnect and hold disconnected said operative connection from said cam to stop movement of said gripper independently of said stitch forming mechanism, and means for disconnecting and holding disconnected from said cam on the cam shaft the operative connection between said cam and said gripper substantially simultaneously with disconnection of said cam on the drive shaft from said gripper.

40 17. The machine set forth in claim 5 with the addition of means including a stationary pointer and an indicator disk on said cam shaft to cooperate with said pointer for presetting the machine to form a predetermined number of stitches prior to operating said thread manipulating means to prevent formation of a loop and slip a stitch.

45 18. In a machine of the character described the combination with work feed mechanism and stitch forming mechanism including a reciprocating needle and a loop taker operable in timed relation for forcing a thread through a piece of work, forming a loop in said thread at one side of the work and interlocking another thread through said loop, and a drive shaft and operative connections between it and said stitch forming mechanism, of a gripper to grip the needle thread above the needle including a pair of opposed relatively movable jaws and a horizontal shaft connected to one end of each jaw for oscillating the jaws in a vertical plane with the needle thread between them, a cam shaft geared for reduced speed to said drive shaft, a cam on said cam shaft and an operative connection between said cam and one of said gripper jaws to control movement of said jaws toward and from the other at intervals to grip and release the needle thread when the needle is approximately in its uppermost position, a cam on said drive shaft, and an operative connection between said cam and said gripper shaft to control oscillation of the latter to swing said gripper approximately synchronously with said needle during a portion of each of the descending and ascending movements of the needle but at a greater speed than the needle during

the first portion of its movement from the limit of its work penetrating position to exert tension on the needle thread and prevent formation of loops.

19. The machine set forth in claim 5 with the addition of means for preventing said operative connection between said cam on the drive shaft and said gripper from engagement with said cam except at intervals corresponding to the intervals at which the gripper grips said thread.

20. In a machine of the character described the combination with work feed mechanism and stitch forming mechanism including a reciprocating needle and a loop taker operable in timed relation for forcing a thread through a piece of work, forming a loop in said thread at one side of the work and interlocking another thread through said loop and a drive shaft and operative connections between it and said stitch forming mechanism, of a gripper to grip the needle thread above the needle including a pair of opposed relatively movable jaws and a horizontal shaft connected to one end of each jaw for oscillating the jaws in a vertical plane with the needle thread between them, means operable in timed relation to the needle for controlling actuation of said movable jaw toward and from the other jaw at intervals to grip and release said needle thread above the needle when the needle is in approximately its uppermost position, a cam on said drive shaft, a follower lever pivoted at one end on a fixed support and connected at its other end to said gripper shaft so as to rotate said gripper shaft in one direction upon movement of said follower lever by said cam to swing said gripper, and a spring for rotating said gripper shaft in the other direction.

21. The machine set forth in claim 1 wherein the means for actuating the gripping means to grip the thread is constructed to actuate the gripping means into gripping relation to the thread only while the needle is at approximately its uppermost position and also is constructed to actuate the gripping means to release the thread when the needle is in said position.

22. The machine set forth in claim 1 with the addition of a positive auxiliary work advancing device ahead of said work feed mechanism operable in timed relation to said stitch forming mechanism to supply the work to the work feed mechanism at a predetermined rate and wherein said work feed mechanism is adjusted to slightly overfeed but move relatively to the work without feeding after the amount supplied by the auxiliary device has been fed, so as to ensure accurate spacing of the skipped stitches.

23. The machine set forth in claim 3 with the addition of a positive auxiliary work advancing device ahead of said work feed mechanism operable in timed relation to said stitch forming mechanism to supply the work to the work feed mechanism at a predetermined rate, and wherein said work feed mechanism is adjusted to slightly overfeed but move relatively to the work without feeding after the amount supplied by the auxiliary device has been fed, so as to ensure accurate spacing of the skipped stitches.

24. The machine set forth in claim 5 with the addition of a positive auxiliary work advancing device ahead of said work feed mechanism operable in timed relation to said stitch forming mechanism to supply the work to the work feed mechanism at a predetermined rate, and wherein said work feed mechanism is adjusted to slightly overfeed but move relatively to the work without feeding after the amount supplied by the

auxiliary device has been fed, so as to ensure accurate spacing of the skipped stitches.

25. The machine set forth in claim 6 with the addition of a positive auxiliary work advancing device ahead of said work feed mechanism operable in timed relation to said stitch forming mechanism to supply the work to the feed dog at a predetermined rate, and wherein said work feed mechanism is adjusted to slightly overfeed 5 but move relatively to the work without feeding after the amount supplied by the auxiliary device has been fed, so as to ensure accurate spacing of the skipped stitches.

26. In a machine of the character described 10 the combination with work feed mechanism and stitch forming mechanism including a reciprocating needle and a loop taker operable in timed relation for forcing a thread through a piece of work, forming a loop in the thread at one side 15 of the work and interlocking another thread through said loop to normally form a line of stitches, of means for gripping said thread at intervals, and means operating in timed relation to the gripping of said thread and the movement 20 of the needle and said loop taker for moving said gripping means while the thread is gripped and in the same direction as the movement of said needle and exerting tension on the thread as the needle rises from work penetrating position and 25 prior to the reaching of loop-taking relation between the loop taker and the needle thread to prevent interlocking of said threads.

27. The machine set forth in claim 26 wherein 30 said gripping means and the means for moving said gripping means and exerting tension on the thread, are operated to maintain the grip on the thread as the needle rises and keep the thread substantially taut between the point of gripping and the needle to prevent entanglement of the 35 surplus thread with the needle.

28. The combination with a sewing machine 40 comprising work feeding mechanism, stitch forming mechanism including a needle and needle thread for forming a line of stitches, and means for causing slipping of stitches at intervals, of means to grip the needle thread, and means for controlling actuation of said gripping means automatically into gripping relation to said needle 45

thread at intervals, and means to move said gripping means while the thread is so gripped to carry to a point above the needle the surplus thread which is present as the result of the slipped stitches.

29. The combination with a sewing machine 5 comprising work feeding mechanism, stitch forming mechanism including a needle and needle thread for forming a line of stitches, and means for causing slipping of stitches at intervals, of 10 means to grip the needle thread, and means for controlling actuation of said gripping means automatically into gripping relation to said needle thread at intervals and to move to a point above the needle the surplus thread which is present 15 as the result of the slipped stitches, said gripping means including two relatively movable opposed jaws to grip the needle thread between them and pivotally mounted at one end to move together in approximately the plane of move- 20 ment of the needle.

30. In a machine of the character described 25 the combination with work feed mechanism and stitch forming mechanism including a reciprocating needle and a loop taker operable in timed relation for forcing a thread through a piece 30 of work, forming a loop in the thread at one side of the work and interlocking another thread through said loop to normally form a line of stitches, of means operable in timed relation to the movement of the needle thread by said needle to automatically manipulate said thread 35 at intervals during normal operation of the stitch forming mechanism and work feed mechanism in forming a stitch to prevent interlocking of said 40 threads; a positive auxiliary work advancing device ahead of said work feed mechanism operable in timed relation to said stitch forming mechanism to supply the work to the work feed mechanism at a predetermined rate, and said work feed mechanism being adjusted to slightly overfeed but move relatively to the work without feeding after the amount supplied by the auxiliary device has been fed, so as to ensure accurate spacing of the slipped stitches.
